UNITED STATES PATENT OFFICE.

ELIOT ARMSTRONG, OF BUFFALO, NEW YORK.

HOSE-SUPPORTER.

1,252,987.

Specification of Letters Patent.

Patented Jan. 8, 1918.

Application filed December 12, 1916. Serial No. 158,428.

To all whom it may concern:

Be it known that I, Eliot Armstrong, a citizen of the United States, residing at Buffalo, in the county of Erie and State of New York, have invented new and useful improvements in Hose-Supporters, of which the following is a specification.

My invention is a garter that is of improved and simple construction, is efficient in performing its functions and possesses important advantages over those heretofore used both from the standpoint of the manufacturer and of the user.

Important advantages result from the extreme simplicity of my improved garter construction, for it consists merely of a single continuous piece of fabric and of three pieces of metal. In making up the garter no stitching of any sort is required for it is assembled quickly and easily by inserting the fabric in slots provided in the metal pieces, and, when so assembled the connection and the position of the parts are maintained by friction.

25 A desirable embodiment of my invention is shown in the accompanying drawing wherein corresponding reference numerals are applied to like parts in the several views.

In the drawing Figure 1 is an isometric or perspective view showing my complete garter in the position to be drawn on to the leg and in the position which it will assume when on the leg. Fig. 2 is a partial view of the preceding showing the securing plate from the back to indicate how that part is adjusted in position on the strip of fabric and Fig. 3 is a view showing a slightly modified form of fastener.

In the drawing 1 indicates the single strip 40 of fabric which is of uniform width and thickness throughout and, preferably more or less elastic. This strip, as shown, is threaded through the slots 8—8 of bangers or fasteners 2—2 which may be of the approved form shown having downwardly contracting openings 4 in which is caught and pinched the small portion of the stocking pulled therethrough by the fingers in the usual manner. As indicated the strip 1 is arranged to form two loops each having a depending fastener 2. Arranged on the strip at the rear is the connecting piece 6, preferably made of thin metal and slightly curved to fit the leg. This piece may be of any suit-

able form and is shown substantially triangular and provided with the slots 6—6 suitably arranged, for instance, two slots at each of its side edges as shown.

To assemble the parts and complete the garter, the strip is inserted through the slots 60 of the metal pieces as shown with the connecting piece at about the middle of the strip, the fasteners being strung onto the opposite end portions of the strip and the ends of the strip are then inserted through the 65 slots in the connecting piece.

As will be seen the strip encircles the leg twice, so that the garter is put on merely by inserting the foot, and there are no cords or other parts to be hooked and unhooked and subject to undesirable wear or abrasion. This is one great advantage of my improved garter that there is no play of one part with reference to another and consequently no abrasion. By the arrangement of the strip around the leg, there is sufficient grip to hold the garter firmly in place under all conditions, and the garter adapts itself by its elasticity to the movement of the leg.

There being no stitching it is easy to assemble the parts and to replace the elastic when worn.

The bangers and connecting piece are preferably made of aluminum or of other light, thin and non-corrosive metal. But as they may be made of any other suitable material, such as leatheroid or celluloid, etc. The contact piece is largely preserved from contact with the person by the strip and therefore is less liable to be corroded or to injure the wearer. The construction and material of this garter may be much modified without departing from the spirit of my invention.

For instance, I have shown in Fig. 3 a desirable modified form of fastener 3 which is provided with three slots in an arrangement which tends to secure the fastener against movement on the strip.

I have thus produced an improved garter wherein the drops for supporting the fasteners are formed by the single strip which provides the double supporting loop as shown. The garter so formed is particularly advantageous in use in that when being positioned on the leg it is unconsciously adjusted and requires no special adjustment for different leg lengths and moreover, does not

depend upon the elasticity of the material or adjustment of a band to retain it properly in place.

Having described my invention I claim,

- 5 1. A hose supporter adapted to be arranged in position by inserting the foot therethrough and comprising a single strip of fabric encircling the leg twice and having the two ends connected together and two hangers connected to and depending from the strip at opposite sides of the leg.
- 10 2. A hose supporter comprising a single strip of fabric arranged to encircle the leg twice and having its ends connected together and two hangers strung on said strip and arranged thereon at a distance from the connected ends and adapted to depend on opposite sides of the leg.
- 15 3. A hose supporter comprising a single strip of fabric arranged to encircle the leg twice, a thin, slotted connecting piece strung on the strip at about the middle of the latter, and the strip ends being inserted in the slots of said piece and maintained therein by friction, and two hangers strung on the strip and depending on opposite sides of the leg.
- 20 4. A hose supporter adapted to be arranged in position by inserting the foot through the supporter, and comprising a

single, continuous strip of elastic fabric arranged in a double circle to encircle the leg twice, a slotted connecting piece of thin metal strung on the strip at about the middle of the latter and adapted to be arranged at the rear above the greatest thickness of calf, the strip ends inserted in the slots of said piece and maintained therein by friction, and two hangers strung on the strip and depending on opposite sides of the leg, said hangers being arranged on the strip at a distance from said piece and on opposite sides thereof.

5 5. A hose supporter comprising a single, continuous strip of fabric adapted to encircle the leg twice, a substantially triangular, thin, metal, connecting piece having two parallel, inclined slots adjacent each side edge, said piece being strung on the strip at about the middle of the latter, and the ends of the strip inserted in the slots and connected to the piece by friction, and two hangers strung on the strip and depending on opposite sides of the leg, said hangers being arranged equi-distant from said piece and on opposite sides thereof.

55 In testimony whereof I have signed my name to this specification.

ELIOT ARMSTRONG.
